UNITED STATES PATENT OFFICE.

HOWARD THURSTON, OF BEECHHURST, NEW YORK.

THEATRICAL APPARATUS.

1,279,042.

Specification of Letters Patent Patented Sept. 17, 1912.

Application filed July 31, 1918. Serial No. 247,488.

To all whom it may concern:

Be it known that I, HOWARD THURSTON, a citizen of the United States, and a resident of Beechhurst, in the county of Queens and State of New York, have invented certain new and useful Improvements in Theatrical Apparatus, of which the following is a specification.

The invention pertains more particularly to stage apparatus involving lighting effects and a specially constructed cabinet, by means of which spirit, ghost and other illusionary effects, may be produced. Aside from the stage and lighting effects, my invention relates in the construction of the cabinet adapted for the uses indicated and being intended to hold several persons.

The cabinet of my invention preferably comprises a raised flooring, a front two-part curtain, two-part side folding doors, rear folding doors, a box concealed within the flooring of the cabinet and pedestals at the rear corners of the cabinet and adapted to permit attendants to stand thereon and be concealed by the rear side and back folding doors when said doors are in their open position. The rear or back doors of the cabinet are hinged to open both inwardly and outwardly, and the cabinet as a whole will be lined with black, and the front curtains and the front side doors will preferably be equipped with hand-holes over which flexible flaps will normally extend. The cabinet of my invention is capable of use in performing various illusionary effects and has been so used successfully by me in public performances.

The details of the construction of my new cabinet, with reference to the accessory features, will be pointed out in full hereinafter and are presented in the accompanying drawings in which:

Figure 1 is a front elevation of the cabinet;

Fig. 2 is a vertical longitudinal section of the same, from front to back, taken on the dotted line 2-2 of Fig. 1 and looking in the direction of the arrow, shown in Fig. 1;

Fig. 3 is a top view of the same;

Fig. 4 is a vertical section through a portion of one of the front curtains of the cabinet taken on the dotted line 4-4 of Fig. 1;

Fig. 5 is a detail illustrating the means

for latching the doors of the cabinet in closed position;

Fig. 6 is a transverse section through the same, taken on the dotted line 6-6 of Fig. 5;

Fig. 7 is a side elevation on a reduced scale of the cabinet with the front and rear lighting effects indicated;

Fig. 8 is a vertical section through the cabinet, taken on the dotted line 8-8 of Fig. 2;

Fig. 9 is a horizontal section through the same, taken on the dotted line 9-9 of Fig. 2, the front curtains being omitted and all of the doors of the cabinet being shown in their open position, and

Fig. 10 is a vertical section through a portion of one of the forward side doors, taken on the dotted line 10-10 of Fig. 2.

In the drawings, 15 indicates a stage of a theater, 16 the cabinet of my invention movably mounted thereon, 17 a forward electric light capable of throwing limited rays of light into the front edge portions of the floor of the cabinet 16, and 18 a rear electric light capable of lighting up the rear portion of the stage and whose rays are excluded from entering the front of the cabinet.

The cabinet 16 has a double flooring 19 and a top 20 and is mounted on legs 21 provided with casters or the like 22, the legs 21 being of appropriate height to permit the audience to look through the space below the flooring 19.

The cabinet is rectangular in transverse section and is sufficiently tall to permit persons to stand therein, and at the front of the cabinet are two curtains 23 which may be slid in a direction from each other so as to open the entire front of the cabinet. The curtains 23 are hung upon rods 24 by means of ordinary curtain rings, and the rods 24 overlap at the center of the front of the cabinet, so that the curtains 23 may, also, overlap each other, as indicated in Fig. 1. The rods 24 at their end portions extend beyond the sides of the cabinet, as indicated at 25, so that the curtains 23 may, when moved to their open position, be extended to hang substantially beyond the sides of the cabinet, thereby exposing the entire interior of the cabinet to the audience. The curtains 23 are provided with hand holes 26 and with flaps 27 which normally hang downwardly.

over and conceal said holes 26, said flaps 27 being secured by sewing or otherwise at their upper edges to the curtains 23. The curtains 23 are of flexible fabric and may be pushed outwardly from each other, on the rods 24, or drawn together to close the front of the cabinet, as illustrated in Fig. 1.

The flooring 19 of the cabinet is formed of double planking leaving a space therein, as shown in Fig. 8, and at the center of the upper layer 28 of the flooring 19 I provide two hinged doors 29 which cover the top of a box 30 concealed within the flooring 19. The box 30 and lids 29 therefor are important in carrying out some of the effects capable of being produced with the use of my cabinet. For illustration, I ordinarily conceal within the box 30 a white gauze ghost costume having a suitable false face annexed thereto and which, without the audience observing the same, is elevated up from the box 30 and placed on an assistant who thereby becomes an illusionary ghost, the curtains 23 at this time being in their open position. The entire inner surface of the cabinet is lined with black, as denoted at 31, this lining being of black velvet or of other material, and while the lamp 18 may light up the back of the stage, the light 17 is so disposed that its rays of light only enter the front of the cabinet to the extent of a few inches, leaving all of the interior of the cabinet entirely dark, or so appearing to the audience, and whereby an assistant effecting the ghost illusion with the use of the box 30 is not observable to the audience.

At each side of the cabinet there are two doors 32, 33, which doors are, respectively, hinged to uprights 34, 35 and correspond in dimensions with each other and adapted to be folded toward each other and to suitable posts 36 extending vertically from the flooring 19 to the top 20 of the cabinet. The forward doors 33 at the sides of the cabinet correspond exactly with the rear doors 32 at said sides, except that the forward doors 33 are formed with hand holes 37 over which are hung flexible flaps 38 corresponding with the flaps 27 of the curtains 23.

At the back of the cabinet are two corresponding rear doors 39, 40 which are hinged to portions of the uprights 34 and may swing inwardly, as shown by dotted lines in Fig. 9, or outwardly, as shown in said Fig. 9. A vertical standard 41 extends from the flooring 19 to the top 20 of the cabinet at a point intermediate the doors 39, 40 when said doors are in closed position, and on the standard 41 may be provided a suitable keeper 42 to coöperate with latches 43 provided on the doors 39, 40 for retaining said doors in normal closed position.

The uprights 36 which stand intermediate the doors 32, 33 when said doors are in

closed position; are also equipped with keepers, numbered 44, to coöperate with latches 45 carried by the doors 32, 33 for locking said doors in closed position. I illustrate in Figs. 5 and 6 the details of construction of the keepers and latches for securing the several cabinet doors in closed position, and these details will be understood without specific description. The invention is not limited to the latching means shown in Figs. 5 and 6, since these means may be varied in many ways and in some instances may be omitted altogether.

At the rear corners of the cabinet are exposed pedestals 46, which pedestals become concealed from the audience when the rear side doors 32 and back doors 39, 40 are opened outwardly against said pedestals or to the position shown by solid line in Fig. 9. The pedestals 46 are of considerable utility and they are intended to receive assistants who will stand on them and themselves become concealed between the aforesaid doors 32, 39, 40. I provide the upper portion of the rear corners of the cabinet with straps 47 (Fig. 2), which may be grasped by the assistants when standing on the pedestals 46 and thereby aid the assistants in maintaining their position on said pedestals.

The cabinet of my invention is capable of use in producing various illusionary and entertaining effects, and these being in the nature of acting or of a performance, need not be gone into in great detail. The cabinet is, as hereinbefore explained, lined with black, and the front light 17 only casts its rays of light to the extent of a few inches into the front of the cabinet when the curtains 23 are opened, and by reason of these conditions assistants, clothed in black, may stand within the cabinet and not be observed by the audience. When the cabinet is placed on the stage, the curtains 23 and the several doors will all be in closed position, and probably two assistants will be concealed within the cabinet. The exterior of the cabinet may then be observed by the audience, and in addition the audience may look below the flooring 19 so as to see that no one is standing behind the cabinet or on the stage near the cabinet. The two assistants, concealed within the cabinet, will, at the proper time, open the back doors 39, 40 inwardly to the dotted position, shown in Fig. 9, and attendants will open the rear side doors 32 outwardly and thereupon the assistants in the cabinet, the doors 39, 40 having been opened inwardly, will step around upon the pedestals 46 and there support themselves, folding the doors 39, 40 outwardly, so that they may be concealed between the doors 32 and said doors 39, 40. The front side doors 33 may then be opened

and the curtains 23 may be moved to open position, whereby the entire interior of the cabinet becomes exposed and the audience may see that no persons are concealed therein. After the audience has been convinced that there is nothing within the cabinet, the front curtains may be closed and the assistants on the pedestals may turn the doors 39, 40 inwardly and step into the cabinet and then close said doors so that they will stand in line with the upright 41. The attendants on the stage will close the doors 32, 33, and at this time the entire cabinet will be in closed condition with two assistants concealed within the cabinet. The assistants may then ring bells or do any acts of performance that might seem to be appropriate and entertaining to the audience. The front curtains 23 may be opened at any time, and the attendants concealed within the back part of the cabinet cannot be observed, due to the blackness within the cabinet.

Performers may enter the cabinet and be forcibly ejected therefrom by the assistants concealed within the cabinet, without the audience knowing in what way the performers became thrown or ejected from the cabinet. A ghost effect may be produced by one of the concealed assistants opening the lids 29 of the box 30 and gradually elevating therefrom a ghost robe having a false face, this robe being applied to one of the assistants by the other assistant concealed within the cabinet. Another effect may be produced by two performers on the stage entering the cabinet and closing the curtains 23 and extending their hands out through the holes 26 therein. While the performers are in this position one or the other may apparently be attacked by the concealed assistants and have his clothes greatly dismantled after which both performers may be ejected from the cabinet by the assistants concealed therein. The concealed assistants may at any time extend bells or other articles through the hand holes 27 of the side doors 33. Various illusory and entertaining effects may be produced with the use of the cabinet, and these may vary with the will of the proprietor of the exhibition.

What I claim as my invention and desire to secure by Letters-Patent, is:

55. 1. A cabinet of the character described having a hinged back door capable of being turned inwardly into the cabinet and also outwardly therefrom, a side door hinged adjacent to the hinged edge of said back door and adapted to be opened outwardly, and an outer pedestal adjacent the hinged edges of said doors upon which a person from within the cabinet may pass and be supported when the said back door is opened

inwardly, said pedestal and the person thereon being between the said back and side doors when said doors are opened outwardly.

2. A cabinet of the character described having two back doors hinged at their outer edges adjacent to the back corners of the cabinet and adapted to be turned inwardly into the cabinet and also outwardly therefrom, two side doors hinged at their rear edges adjacent to the hinged edges of said back doors and adapted to be opened outwardly, and outer pedestals at said back corners upon which persons from within the cabinet may pass and be supported when the said back doors are opened inwardly, said pedestals and the persons thereon being between said back and side doors when said doors are opened outwardly.

3. A cabinet of the character described having a hinged back door capable of being turned inwardly into the cabinet and also outwardly therefrom, a side door hinged adjacent to the hinged edge of said back door and adapted to be opened outwardly, and an outer pedestal adjacent the hinged edges of said doors upon which a person from within the cabinet may pass and be supported when the said back door is opened inwardly, said pedestal and the person thereon being between the said back and side doors when said doors are opened outwardly, said cabinet also having a dark lining and front curtains.

4. A cabinet of the character described having two back doors hinged at their outer edges adjacent to the back corners of the cabinet and adapted to be turned inwardly into the cabinet and also outwardly therefrom, two side doors hinged at their rear edges adjacent to the hinged edges of said back doors and adapted to be opened outwardly, and outer pedestals at said back corners upon which persons from within the cabinet may pass and be supported when the said back doors are opened inwardly, said pedestals and the persons thereon being between said back and side doors when said doors are opened outwardly, said cabinet also having a dark lining, front curtains and a receptacle in its flooring.

5. A cabinet of the character described lined with black and having two hinged back-doors, two hinged doors at each side, front flexible curtains and in its flooring a receptacle, the front side doors having openings therein and flaps therefor.

6. A cabinet of the character described lined with black and having two hinged back doors, two hinged doors at each side, front flexible curtains and in its flooring a receptacle, the front side doors having curtains having openings therein and flaps therefor.

7. A cabinet of the character described having hinged back and side doors, front curtains, and an exterior elevated support for a person, said support being between adjacent doors when such doors are in open position and to be concealed thereby.

8. A cabinet of the character described having back and side doors, front laterally slidable curtains, and supporting rods for said curtains, said rods overlapping each other at the front of the upper part of the cabinet and at their ends being carried beyond the sides of the cabinet and having return bends, whereby the curtains may be moved laterally to expose the entire front of the cabinet.

9. A cabinet of the character described having a dark lining, hinged back and side doors, front curtains and a covered receptacle within its flooring, said receptacle being

25
ing back from the front of the cabinet, and lighting means adapted to direct its rays only into the lower extreme front portion of the cabinet and to the front of said receptacle.

10. A cabinet of the character described having a dark lining, a hinged back door, a side door hinged adjacent to the hinged edge of said back door, and an exterior support upon which an attendant may be concealed by said doors when said doors are opened outwardly toward each other.

30
Signed at New York city, in the county of New York and State of New York this 29th day of July, A. D. 1918.

HOWARD THURSTON.
